SIGNAL INSTRUMENT.

Application filed March 16, 1925. Serial No. 15,910.

This invention relates to instruments for recording telegraphic and other signals upon a paper tape, and is particularly suited for embodiment in signal instruments employed 5 in fire alarm, police telegraph and other emergency signaling systems.

A variety of types of signal instruments have heretofore been devised for use in situations presenting a corresponding variety 10 of operating conditions, and, because no one type of such prior signal instruments has been found to be suited to all or any considerable proportion of such diverse operating conditions, the custom has become prevalent 15 of manufacturing and using almost as many varieties of such instruments as there are different varieties of operating conditions. For example, signal instruments in fire houses in smaller communities, where the 20 circuits connecting fire house instruments also include slow acting mechanism such as tower bell strikers and whistle machines, and the interpretation of alarms is likely to devolve upon volunteer firemen who are 25 untrained in the reading of signaling tapes, it has been found desirable to employ comparatively slow acting punch recorders which produce a record comprising comparatively large openings punched through 30 a wide slow moving paper tape, notwithstanding the fact that such recorders are incapable of acting with sufficient rapidity to render them suitable for use in fire alarm systems in larger cities where (because slow 35 acting mechanism is not included in the circuits with fire house instruments) the formulation of fire house signals is at a rate from four to eight times as rapid as in some of the smaller communities. Then again 40 there is the distinction between signaling systems such as those used for municipal fire alarm purposes where there is, in effect, but one class of signals, and systems such as municipal police signaling and combined 45 watchman and fire alarm systems in which different classes of signals are differentiated, one from another, through the utilization of code signals comprising circuit closures or circuit breaks of differing time characteristics. 50 Because of the limited character of the fields for the utilization of such a multiplicity of types of signal instruments, it has been found to be impracticable to manufacture any one type in sufficient quantity to

justify the adoption of production methods 55 such as would bring about substantial reductions in time consumed and cost incurred in manufacturing while greatly increasing the uniformity of the dependability and durability of the product were 60 like parts and instruments rendered available for all or a very large proportion of the various operating conditions.

It is, therefore, an important object of this invention to provide a type of signal 65 instrument the constituent parts of which may be variously assembled and adjusted so that a single form of assembly of such parts will be suited for use in many practical operating conditions, and so that not 70 more than two or three forms of such assembly will cover practically all of such operating conditions.

The prior forms of signal instruments 75 which were suited for uses such as just referred to, have embodied parts whose construction and arrangement as to cooperative relationship have been such that intended operation thereof has tended to develop a condition of inoperability, of which condition there would be little if any indication discernible through ordinary observation and inspection, until such process of deterioration progressed to a degree resulting 80 in suspension of operation of the instrument. For reasons well understood by those skilled in this art, such suspensions of operability are highly objectionable in the signal instruments of emergency signaling systems, and are likely to be the controlling 85 factor in permitting the development of disasters involving extensive losses of life and property.

It is, therefore, a further general object 90 of this invention to provide a signal instrument suited to uses such as already referred to, having formation and arrangement of parts whereby deterioration due to operation will be greatly retarded, as compared 95 with prior art instruments.

Signal instruments suited for uses such as hereinbefore referred to, comprise paper feeding mechanism involving self-starting and self-stopping means whereby operation 100 of the feeding mechanism is initiated at the first stroke of each signal and is thereafter continued throughout the signal and until the expiration of a time, measured by the 105

running of the mechanism, which time is usually longer than the longest interval between strokes or impulses of any signal. In prior art instruments of this kind, such starting and stopping means has included a member (commonly termed a "hopper") operable, by engagement with a part of the paper feeding mechanism, for movement of such member toward a position where it will cause the operation of such mechanism to be arrested; which member is arranged for disengagement from such cooperating part upon each actuation of the marking mechanism, and is thereupon moved to a position from which its actuation by the running of the paper feeding mechanism to a position where it will arrest the running thereof can be accomplished only following predetermined operation of such mechanism. It has been found that the operation of such paper starting and stopping mechanism causes comparatively rapid deformation of the co-engaging surfaces of such hoppers and the actuating parts therefor, so that operative failures occur whereby the feeding mechanism is not started when it should be (thus failing to cause movement of the paper such as will enable the first strokes of signals to be properly recorded), and so that the starting mechanism does not so act as to assure sufficient run of the feeding mechanism following every stroke of the signal (thus causing a misleading record by fore-shortening representations of intervals between strokes within a signal because of the stopping of the feed during such intervals), or by failing to stop the paper feeding mechanism at the proper time, and thus not only wasting the paper tape but, incidentally, carrying the last signal so far from the register that—under many operating conditions—the portion of the tape upon which the signal has been marked will be wound upon an automatic paper winder, or in some other way, will pass beyond the range of vision of the operator.

It is, therefore, a specific object of this invention to provide automatic starting and stopping means for the paper feeding mechanism the cooperating parts of which will not be subjected to such rapid deterioration, and which will dependably operate for a long period without adjustment, repair or renewal of parts.

In the use of prior art signal instruments, it has been found that inequalities in the thickness of the paper tape passing between the rollers of the feeding mechanism—such as sometimes result from the presence of lumps or foreign matter in the paper or from the folding under of the partially cut away tongues cut in the tape of certain forms of instruments—cause diversion in the direction of movement of the tape such that the edge of the tape is forced against the

side of the guide in which it moves, thereby causing irregularity in the speed of tape travel and, in extreme cases, causing suspension of the operation of the paper feeding mechanism, or whereby the tape is diverted from the path of either or both the marking mechanism and the feed rollers.

It is, therefore, a further specific object of this invention to provide, in signal instruments of the character referred to, paper feeding mechanism such that the direction of tape travel will not be appreciably altered because of irregularities in the thickness of the paper tape or because of the passage through such feeding mechanism of folded under tongues cut in such paper.

In the practical use of signal instruments such as hereinbefore referred to, the environment is sometimes such that it is desirable that, following the last stroke of each signal, the movement of the paper tape be arrested soon after it has carried the record of the signal clear of the signal instrument, so that the entire record will be visible between the instrument and any automatic paper winding device which may be provided adjacent thereto for winding up the paper after it has been delivered from the instrument and the signal has been read therefrom. In other environments, the signal instrument may be placed in a cabinet or be mounted adjacent to a so-called "automatic time stamp" or other mechanism, whereby the tape is shielded from vision for a substantial distance beyond the signal instrument; so that, in such cases, it is desirable that the movement of the tape shall not be arrested, following the last stroke of any signal, until the tape has traveled far enough to carry the signal outside of such cabinet or beyond such a time stamp or other instrument. It has thus become customary to assemble such signal instruments only upon a specific order designating the required tape travel following last stroke of signal, as to do otherwise would necessitate taking down and reassembling stock instruments in order to convert those suited for one class of service to another. Such procedure not only incurs greatly increased cost of manufacture and assembly, due to inability to apply bulk production methods,—but also greatly delays delivery of such instruments on orders.

It is, therefore, a further specific object of this invention to provide signal instruments of the character hereinbefore referred to whose feeding mechanism is arranged for adjustability of extent of paper feed after last strokes of signals, so as to provide for all variations in operating conditions without change of parts or reassembly of the instrument.

As hereinbefore referred to, signal instruments of the character described are sometimes used in connection with paper wind-

ing mechanism or so-called "take-up reels", and circumstances of environment sometimes require that such winding mechanism shall be located in much closer proximity to the signal instrument than in other cases. Although it is almost invariably considered desirable that the openings cut in the paper tape of such instruments shall be as large as circumstances permit, it is obvious that in those situations where a comparatively small length of tape may be exposed between the take-up mechanism and the signal instrument, the record of the signal should be condensed, in order that a complete signal may be exposed. In order to enable bulk production methods to be employed in the manufacture of such signal instruments and, at the same time, to enable them to be suited to varying conditions of maximum length of signals to be recorded and variations in length of exposed tape, it is necessary to supplement adjustability of extent of tape run after last stroke by facilities for readily adjusting speed of tape feed and the size of the mark produced by the openings cut in the tape; so that when conditions make it necessary to reduce the speed of tape travel with relation to the speed of signal reception, in order to enable entire signals to be visible between the signal instrument (or the associated time stamp, if any) and the paper winding mechanism, the size of the opening in the tape may be readily altered so that the marks will be properly spaced notwithstanding such decrease in relative tape speed; and so that when conditions permit a faster relative tape speed the sizes of the openings cut in the paper can be correspondingly increased.

It is, therefore, a further specific object of this invention to provide, in signal instruments of the character described, a form of marking mechanism which will permit the size of marks to be altered, to compensate for changes in relative rate of tape travel, as just described.

In the use of signal instruments of the character hereinbefore referred to, conditions are frequently encountered in which it is necessary or highly desirable to provide circuit controllers operable in timed relation to the signals recorded thereby for the control of associated time stamps, hummers, emergency bells for police signaling systems and for combined night watch and fire alarm systems, and other similar purposes, as is well understood by those skilled in this art. Differing conditions of environment, such as have been referred to in connection with the foregoing objects, as well as different relationships between speed of paper feed and signaling speed, require the establishment of different relationships between the commencement and completion of recorded signals and the times at which vari-

ous ones of such contacts shall become effective.

It is, therefore, a further specific object of this invention to provide an instrument of the character hereinbefore referred to having circuit controlling means adjustable throughout the scope of variations needed to meet service conditions, without diversity of original assembly and without taking down and reassembling instruments in order to suit them for changed operating condition.

Other objects are to render the various parts more economical in production, more reliable in operation and more durable in service than corresponding parts of prior signal instruments. Still other objects will be in part apparent as the description of this invention proceeds, and, in part, will be hereinafter more specifically referred to.

To enable others skilled in the art so fully to comprehend the underlying features thereof that they may embody the same by the numerous modifications in structure and relation contemplated by this invention, drawings depicting a preferred form have been annexed as part of this disclosure, and in such drawings, like characters of reference denote corresponding parts through all of the views; of which:

Figure 1 is a front elevation of a signal instrument embodying this invention, portions of the side plate, base and other parts being shown broken away for the purpose of more clearly disclosing certain features of construction;

Fig. 2 shows alternative construction and arrangement of certain parts of the mechanism of the instrument of Fig. 1;

Fig. 3 is a perspective view of the mechanism of the instrument of Fig. 1, with the frame plates removed and parts broken away and omitted for the purpose of more clearly disclosing the operative relationships of the parts shown;

Fig. 4 is an enlarged view, partly in section, of certain of the mechanism of Fig. 3;

Fig. 5 shows the cooperative relationship between contact controlling mechanism and certain portions of the mechanism of Fig. 3;

Fig. 6 shows an alternative form of one of the sets of the contacts of Fig. 5; and

Figs. 7 and 8 are enlarged detail views of certain of the parts shown by Fig. 3.

The signal instrument represented by the accompanying drawings is arranged for independent response to two circuits and comprises paper feeding mechanism involving the feed rollers 21 and 22 for propelling suitable tape, such as the paper tape 23 (see Fig. 1), together with marking mechanism involving the cutting tools 24 and 25 (see Fig. 3) and controlling magnets 26 and 27. Said paper feeding and marking mechanisms are driven by motor mechanism com-

prising the main driving gears 28 and 29, which are carried by the shaft 30. One of said main gears is fixed upon said shaft and the other of said gears is arranged for rotation independently of said shaft and carries the drum 31. A motor spring (not shown) is enclosed in said drum; one end of said spring being connected to said drum and the other end thereof being connected to said shaft, so as to tend to rotate said gears 28 and 29 clockwise and counter-clockwise, respectively, as indicated by the arrows shown in Fig. 3. Detailed arrangement of a motor spring, suitable for employment here, is shown by Patent No. 726,882, issued to H. W. Doughty and C. E. Beach and dated May 5th, 1903, and is well understood by those skilled in this art, and will therefore not be further described herein.

The pinions 32 and 33 fixed upon the sleeves 34 and 35, are engaged by the gears 28 and 29, respectively, and said sleeves are carried by the shaft 36 for rotation independently thereof. The gears 37 and 38 are also fixed upon the sleeves 34 and 35, respectively, so as to be driven by the gears 28 and 29 acting through the pinions 32 and 33, respectively. The pinion 39 is engaged by the gear 37, and said pinion, together with the ratchet wheel 40 and gear 41 are carried by the shaft 42; said pinion and ratchet wheel being arranged to move together and said gear being arranged to move independently thereof and being connected with said ratchet wheel by means of the dog 43 so that said gear will be positively driven by the energy of the main spring as applied to the pinion 39. The pinion 44 is driven by the gear 41, and the gear 45 moves with said pinion, both of which are fixed upon the shaft 46, which shaft also carries and drives the feed roller 21. The gear 45 acts through the pinion 47 to drive the shaft 48 upon which is fixed an escapement wheel 49, a pair of eccentrics 55 and 56 carried by the bosses 50, 50, respectively, and a detent arm 51. The escapement wheel 49 is engaged by a pallet 52 which is fixed upon the shaft 53, which shaft also carries the pendulum 54 which is adjustable for regulating the speed of rotation of said wheel 49—and, hence, that of the feed roller 21. As best shown by Fig. 4, the eccentrics 55 and 56 (which are carried by the bosses 50, 50, respectively) are arranged in diametrically opposite relationship and carry the pawls 57 and 58, respectively. The ratchet wheel 59 is fixed upon the shaft 60, and said wheel is arranged for actuation in response to the alternate reciprocation of the pawls 57 and 58 incident to the rotation of the shaft 48. The detent lever 61 is also fixed upon the shaft 60, and is arranged for cooperation with the arm 51 for the purpose of arresting rotation of the shaft 48 whenever said lever 61 is in a certain position. It will be noted that the shaft 48 is arranged for clockwise rotation, i. e., so that, during the rotation of the eccentrics 55 and 56, the upper surfaces thereof will move toward the ratchet wheel 59, for a purpose which will be hereinafter more fully explained. An arm 62 is loosely mounted upon the shaft 48 between the pawls 57 and 58, which arm carries bent-over projections 63 and 64 which are arranged for engaging the pawls 57 and 58, respectively, for the purpose of urging them toward the wheel 59. A spring 65 is so applied to said arm 62 as to urge movement of same in such direction as will tend to carry the projections 63 and 64 in the direction of the pawls 57 and 58. The extent of the eccentricity of the eccentrics 55 and 56 is so proportioned to the pitch of the wheel 59 that each revolution of the shaft 48 may cause rotation of the shaft 60 for an angular distance corresponding with that between adjacent teeth of the wheel 59, and the height of the teeth of said wheel is so proportioned to the throw of said eccentrics that, due to the direction of rotation hereinbefore just defined, the top of whichever one of the pawls 57 and 58 is at any time driving the wheel 59 will be lifted by its actuating eccentric to a higher level than that of the one of said pawls which is at any such time being withdrawn over an advancing tooth of said wheel. It will be observed that, as a result of this construction, the spring 65 will act through the arm 62 to urge toward the wheel 59 whichever of the pawls 57 and 58 should, at that time, act to move said wheel, but whichever pawl is, at any time, riding over the back of a tooth of said wheel, will be permitted to move in response to the lifting action of such tooth without opposition from the spring 65 acting through the arm 62, thereby greatly decreasing the wear of these parts incident to the operation of the mechanism.

The pinion 95 is fixed upon the shaft 96 which has a squared end 97 (see Fig. 3) for cooperation with a winding member, such as the handle 98 (see Fig. 1).

The gear 101 and boss 102 are fixed upon the shaft 103, and said gear is driven by the gear 38, acting through the pinion 104.

The pinion 105 is pivotally mounted upon the boss 102, and the gears 106 and 107 are carried by the shaft 103, for rotation independently thereof, and are situated at respective sides of said pinion 105 for cooperation therewith so as to provide a differential drive. The escape wheels 108 and 109 rotate with the gears 106 and 107, being respectively connected therewith by said sleeves 110 and 111. The pallets 112 and 113 are so mounted that an oscillatory motion will be imparted thereto by the rotation of the shaft 103.

tion of the wheels 108 and 109, respectively; such pallets being fixed upon the sleeves 114 and 115, respectively. The arms 116 and 117 are also fixed upon the sleeves 114 and 115, respectively, and said sleeves are, in turn, carried by the shaft 118; said sleeve 114 being arranged for rotation independently of said shaft, and said sleeve 115 being fixed upon said shaft. The arms 120 and 121 are also carried by the portion of the shaft 118 which extends outside of the frame of the machine (a portion of said shaft being shown broken away in Fig. 3, in order to better disclose other parts of the mechanism which will be hereinafter referred to) and the cutting tools 25 and 24 are secured to the free ends of said arms, respectively. The arm 120 is fixed upon the shaft 118, and therefore moves with the pallet 113; and the arm 121 is correspondingly arranged to move with the pallet 112, being operatively connected therewith through the bar 119, the arm 116 and the sleeve 114.

As best shown in Fig. 8, it will be noted that the cutting tools 24 and 25 are provided with elongated openings 20 for receiving the screws 19 provided for attaching said tools to their respective arms. The length of the openings 20 is such as to permit relative adjustment between said tools and their associated arms so that upon intended movement of such arms, the cutting portions of said respective tools will be moved through the plane in which the tape 33 is moved a greater or lesser distance for a purpose which will be hereinafter more fully explained.

The bell crank levers 122 and 123 are pivotally mounted upon the shaft 124 for independent movement, said lever 122 being connected through the link 125 with a downwardly extending portion of the arm 116, and the lever 123 being correspondingly connected with the arm 117.

The inverted V-shaped pins 126 and 127 are carried at the free ends of the arms 122' and 123' of the bell crank levers 122 and 123, respectively, for a purpose which will be hereinafter more fully explained; and the stop pins 128 and 129 are mounted in the paths of said arms 122' and 123', respectively, so as to limit the upward movement thereof. The arm 122' and link 125 are so arranged as to provide a toggle action, and the pin 128 is so positioned as to prevent the bell crank lever 122 being rotated in a clockwise direction far enough to raise the free end of the arm 122' high enough to bring the centers of the points of attachment of the link 125 to said arm 122' and to the arm 116 into alignment with the axis of the shaft 124.

The length of the link 125, and the arrangement of the associated parts, is such as to permit movement of the arm 116 in-

cident to the passage of teeth of the wheel 108 under the upper end of the pallet 112, and such that the inception of the movement imparted to said arm 116 by the engagement of the teeth of said wheel 108 with the lower arm of said pallet 112 will cause the bell crank lever 122 to swing downwardly.

Inasmuch as the toggle connection between the lever 123 and the arm 117 corresponds with that between the lever 122 and the arm 116, as shown by Fig. 3 and just described herein, the toggle action connecting said lever 123 and said arm 117 is not shown by the drawings, and will not be here further described.

The armatures 135 and 136 are mounted in cooperative relationship with the poles of the electromagnets 26 and 27, respectively, said armatures being carried by the shaft 137, and arranged for independent movement. Retractile springs 138 and 139 are provided for the armatures 135 and 136, respectively, and the upright arms 140 and 141 are arranged for movement with said armatures, respectively, the upper end of each of said arms being provided with a set of pawls, said sets of pawls being arranged for engagement with the pins 127 and 126, respectively. The relationship between said pawls and the pins 126 and 127 is such that they may serve to maintain the arms 122' and 123' adjacent their stop pins 128 and 129, respectively. Each set of said pawls is so arranged that final release of their respective associated pins may be caused to occur either upon attractive or retractive movement of the armature by which it is controlled, and the general construction, arrangement and operation of said pawls is analogous to that of corresponding mechanism which is disclosed in greater detail and fully described in my Patent No. 1,478,901, dated December 25th, 1923, to which reference is had. The construction and arrangement of the respective ones of such sets of pawls with relation to their cooperating pins is such that each cycle of movement of the armature 136 will permit a cycle of movement of the pallet 112 by causing disengagement of the pin 126, and each cycle of movement of the armature 135 will correspondingly permit a cycle of the movement of the pallet 113. From the foregoing, it will be seen that the magnet 27, armature 136, arm 141, lever 122 and associated parts may be properly considered as forming parts of means for controlling the marking mechanism comprising the cutting tool 24; and that the magnet 26, armature 135, arm 140, lever 123 and associated parts correspondingly provide means for controlling the marking mechanism comprising the cutting tool 25.

The projections 148 and 149 are also carried by the arms 140 and 141, respectively, near the free ends thereof, for a pur-

pose which will be hereinafter more fully explained.

The arms 150 and 151 are fixed upon the shaft 152, and are situated in the paths of the arms 116 and 117, respectively; and the arm 153 moving with said shaft 152 carries the crossbar 154 at the free end thereof, one end of which crossbar extends beneath the pawls 57 and 58 and the other end of which bar cooperates with the latch 155. Said parts are so relatively arranged that each cycle of movement of either the pallet 112 or pallet 113 will cause the associated arm 116 or 117—as the case may be—to act through the associated arm 150 or 151, respectively, to so elevate the arm 153 as to cause one end of the bar 154 to lift the pawls 57 and 58 out of engagement with the wheel 59 and to bring the other end of said bar 154 to a position where it may be retained by the latch 155. The spring 156 so connects the arm 153 and the latch 155 as to tend to move the free end of said arm downwardly and so as to cause said latch to engage the bar 154. An end 157 of said latch 155 is so formed as to project into the path of the arm 51 carried by the shaft 48 when said latch is positioned for supporting the bar 154, so that the rotation of said arm 51 may cause disengagement of said latch from said bar 154.

A spring 66 is so applied to the shaft 60 as to tend to rotate same in counter-clockwise direction, as viewed in the drawing, and a pin 67, carried by the revoluble bushing 68 projects in the path of the lever 61 for limiting the extent of the rotation of said shaft 60 in response to said spring 66. Said bushing 68 extends through the frame plate 69 and carries a knurled handle 70, by means of which said bushing may be rotated for the purpose of increasing or decreasing the extent of permitted rotation of the shaft 60. A set screw 71 is provided for retaining the bushing 68 in the positions to which it may be set by means of the handle 70.

A guide plate 81 is provided for supporting the paper tape upon which signals are recorded, said plate being provided with openings 82, 82 for receiving the cutting tools 24 and 25 and an opening 83 for the feed roller 21.

The cutting tools 24 and 25 are so adjusted on the free ends of their respective carrier arms 121 and 120, that, when either of said arms is in its normal fully elevated position the point of the cutting tools carried thereby will be spaced away from the plate 81 at least far enough to permit the passage of paper tape therebetween; and each of said cutting tools may be set relative to its carrier arm at various greater distances from said plate 81, to the end that, upon the downward movement imparted to said

arms incident to the rotation of the wheels 108 and 109 with which they are respectively associated, said cutting tools may be caused to penetrate such tape, and to enter the openings 82, 82 a greater or lesser distance, to the end that the sizes of the openings thus produced in the paper tape may be varied for purposes hereinafter more fully explained.

A flexible pressure piece 84 rests upon the upper surface of the plate 81, and extends between the openings 82, 82 therein, and carries at the free end thereof a T-bar 85 which extends between said openings and the feed roller for purposes which will be hereinafter more fully explained.

The feed rollers 22, 22 are pivotally attached to the respective sides of the pressure bar 86 which is pivoted at 87 and carries a flat spring 88 for urging same toward the roller 21. As best shown in Fig. 7, the opening through the bar 86 for the pivot 87 is relieved toward both sides of said bar, so as to permit said bar to rock relatively to said pivot, on an axis substantially perpendicular to that of the roller 21, to such extent as to enable the rollers 22, 22 to assume various relationships with the roller 21 and thereby compensate for irregularities in thickness of the paper tape passing over the roller 21, especially such as result from the folding under of tongues cut in the paper by the cutting tools 24 and 25. Releasing means comprising the cam 89 is provided for lifting the bar 86 so as to facilitate insertion or removal of paper tape.

The insulating block 72 is mounted adjacent to the shaft 60 and carries three sets of normally separated contacts as generally indicated at 73, 74 and 75, respectively. An arm 76, which is frictionally secured to the shaft 60 by means of the clamping screw 77, carries an insulating rod 78 for actuating the contacts 73 and 74; the parts being so arranged that said contacts may be closed by said rod during the clockwise rotation of the shaft 60, and preferably so that, after the contacts are so closed, further clockwise rotation of said shaft will permit them to again open. Such contacts may be variously utilized, to suit differing service conditions; the utilization suggestively indicated by Fig. 5 involving the employment of the contact 73 for control of a hummer and involving the employment of the contact 74 for the control of the printing circuit of such time stamp as may be associated with the register. If it is desired to provide normally open contacts for the control of a bell or lamp to give warning whenever the register is acting in response to a signal, or for the purpose of shunting out a routine signaling in a manner analogous to that shown by Patent No. 1,274,367, issued to C. E. Beach and dated August 6th, 1918; and which

should, therefore, close at the commencement of paper feed run and remain closed until just before the paper feeding mechanism comes to rest, the contacts 79 of Fig. 6, may be substituted for either the contacts 73 or 74 of Fig. 5. It will be noted that the contacts 79 are arranged for co-operation with the rod 78 in such manner that, when said rod is in the position which it occupies when the detent lever 61 is disposed in the path of the detent arm 51, said rod 78 will hold the contacts 79 apart; and so that, when the lever 61 has moved out of the path of the arm 51, said rod 78 will be withdrawn from the path of the contacts 79 and will therefore permit said contacts to close. Inasmuch as the purposes and manner of utilizing contacts controlled by the starting and stopping mechanism of signal instruments is well understood by those skilled in this art, it will not be further herein described.

A so-called "creeper attachment" is provided for controlling the contacts 75 for purposes which will be hereinafter more fully described. This attachment comprises a flexible arm 161, one end of which is attached to the frame plate at 162 and the other end of which is provided with an ear 163 to which a sector 164 is pivotally attached, as shown in Fig. 1 (analogous parts bearing similar reference characters being somewhat more clearly shown in Fig. 2). A spring 165 is so applied to the sector 164 as to tend to swing same to the right, as viewed in the drawing, and a set screw 166 is carried by the arm 161 in such position as to serve as an adjustable stop for limiting the extent of the movement imparted to said sector by said spring.

An insulating projection 167 is carried by the sector 164, and said projection is so formed that it may be brought into actuating engagement with the contacts 75, by movement of said sector against the tendency of the spring 165.

The sector 164 is so situated that the periphery thereof may be brought into contact with a part moving with the paper feeding mechanism, the direction of movement of which part is such as to tend to so move said sector to bring the projection 167 into engagement with the contacts 75. In the interests of clearness of disclosure, the sector 164 of Fig. 1 is shown positioned over the paper tape 23, so as to be operable thereby when the arm 161 is depressed in a manner hereinafter more fully explained. For classes of services in which it is desirable that the creeper attachment shall function irrespective of the continuity of paper tape, such as the tape 23, it is preferable that the sector 164 shall be mounted in cooperative relation with some part of the paper

feeding train, such, for example, as the feed roller 21, as indicated in Fig. 2.

The arms 168, 169 and 170 are carried by the shaft 171, to which they are detachably secured, as by means of the cotter pin 172 shown in the boss of the arm 170. The free end of the arm 168 carries a pin 173 which is positioned for engagement with an adjustable anvil-screw 174 carried by the arm 161 intermediate the ends thereof. The arms 169 and 170 are so formed and positioned for such cooperative relationship with the projections 149 and 148, respectively, that movement of either the armature 136 or 135 from normal to abnormal position will cause rotation of the shaft 171 such as to cause the pin 173 to act through the screw 174 to move the arm 161 to the position which will cause actuation of the sector 164 against the tendency of the spring 165. For example, when the parts are arranged for normal energization of the electromagnets (as indicated by Figs. 1 and 3) the arms 169 and 170 are so formed that movement either of the projection 148 or the projection 149 will cause such depression of the arm 161 as to bring the sector 164 into engagement with the part by which it may be moved, against the tension of the spring 165. When the instrument is adjusted for control by normally open circuits, the parts are arranged as indicated by Fig. 2, the arms 169 and 170 being interchanged so that the attraction instead of the retraction of either armature will cause depression of the arm 161 or 161', as the case may be.

It will be noted that the shaft 171 is the same diameter throughout its length, so that it may be moved endwise through the openings provided therefor in the frame plates and thereby facilitate interchanging of the arms 169 and 170, without otherwise taking the instrument apart and reassembling it.

A signal instrument embodying parts such as hereinbefore described in greater detail, and arranged as indicated by Figs. 1 and 3, will be suited for response to circuits which are normally closed and to which significant response should be made by the recording instrument upon the occasion of each break in the continuity thereof. If it is desired to convert an instrument assembled as just described, so as to suit same for response to circuits which are normally open, the positions of the arms 169 and 170 upon the shaft 171 should be changed, as hereinbefore just explained, and the pawls carried by the free ends of the arms 140 and 141 should be correspondingly changed in position as more fully explained in my Patent No. 1,478,901, dated December 25th, 1923. It will be understood that in the event that the emergency signal contacts 75 will not be required, under the operative conditions in which the

instrument is to be employed, it will be unnecessary to interchange the arms 169 and 170.

If the instrument is to be used in a situation where legibility of the tape records of signals is deemed more important than compactness of such records, the cutting tools 24 and 25 should be moved downwardly, relative to their respective supporting arms 121 and 120, as far as may be without bringing the points of said tools into the path of paper tape passing between the pressure piece 84 and the guide plate 81, and such tools should then be secured in position by means of the attachment screws 19 provided therefor. The pendulum 54 should be adjusted with relation to the speed of signal formulation in the circuit to which the instrument is to respond so as to space the markings produced upon the tape by the instrument in a manner which will facilitate reading thereof; to this end, the pendulum 54 shown may be removed from the shaft 53, and a similar pendulum either lighter or heavier than that shown may be substituted therefor, without otherwise taking down and reassembling the mechanism of the instrument. Ordinary speed adjustments may be effected without such exchange of pendulums, in a manner well understood by those skilled in this art.

The operation of signal instruments such as hereinbefore described, is as follows:

Assuming that the main spring has been wound as by the use of the winding handle 98, that suitable tape 23 is in position on the guide plate 81 and is gripped between the rollers 21 and 22, and that the windings of the electromagnets 26 and 27 are connected in the desired signaling circuits,—while such circuits remain closed, the parts will be at rest, relatively positioned as indicated in Figs. 1 and 3. If, while the parts are so positioned, the magnet 27 becomes deenergized,—the spring 139 will so swing the arm 141 as to carry the armature 136 away from said magnet and so as to cause the pawls carried by said arm to release the pin 126 and thereby permit the bell crank lever 122 to move in a counter-clockwise direction. Said lever 122 will thereupon so move, in response to gravity supplemented by the tendency imparted to said lever by the thrust applied to the lower end of the pallet 112 by the wheel 108, so as to break the toggle formed by the arm 122' of said lever in cooperation with the link 125, and thereby permit said wheel 108 to act through said pallet 112, said arm 116 and the bar 119, to cause the arm 121 to force the cutting tool 24 to penetrate the paper tape 23 and enter one of the openings 82 and thereby form a tongue in said paper which will be inclined downwardly, as more fully explained in Patent No. 938,285, dated Oct. 26th, 1909. After

the tool 24 has been thus caused to penetrate the tape, continued rotation of the escape wheel 108 will cause same to act against the upper end of the pallet 112, so as to rock the arm 116 and parts moving therewith to a position which will carry the tool 24 and the pin 126 somewhat higher above the tape 23 and the pawls carried by the upper end of the arm 141, respectively, than the positions normally occupied by these parts. Such movement of the pallet 112 will carry the upper end thereof out of the path of the escape wheel 108 and will carry the lower end thereof into the path of said wheel, which will thereby tend to cause a repetition of the cycle of operation just described. Inasmuch, however, as the pin 126 will now be situated above the pawls carried by the free end of the arm 141, one or the other of such pawls will be disposed in the path of said pin (depending upon the position of the armature 136, and, hence, of the arm 141) and said pallet 112, the escape wheel 108, and the parts moving therewith, will therefore be brought to rest. It should be noted that, when the escape wheel 108 is brought to rest, as just described, the pallet 112 is so positioned as to be operable by said escape wheel at least advantage, thereby minimizing the frictional resistance to movement of the pawls carried by the arm 141 resultant from the support thereby of the pin 126.

The initial movement of the arm 116, incident to the cycle of action of the pallet 112 as just described, will cause said arm to act through the arm 150, shaft 152, arm 153 and bar 154 to lift the pawls 57 and 58 out of the path of the teeth of the wheel 59; whereupon said wheel will be rotated by the spring 66, so as to carry the detent lever 61 out of the path of the detent arm 51 and thereby release the paper feeding train.

When the bar 154 is raised, as just described, so as to lift the pawls 57 and 58 out of the path of the teeth of the wheel 59, the latch 155 is moved by the spring 156 so as to retain said bar in such raised position; thereby preventing reengagement of said pawls with said teeth when the arm 116 has returned to its normal position.

Upon release of the paper feeding train, as just described, said train will commence operation in response to driving force applied by the gear 28, whereupon the rotation of the shaft 46 will cause the roller 21 to drive the paper tape 23 and the rotation of the shaft 48 will cause the eccentrics 55 and 56 to impart a reciprocating movement to the pawls 57 and 58, respectively; but, because of the supporting action of the bar 154, such movement of said pawls will not cause actuation of the wheel 59. The movement of the tape 23 incident to the rotation of the roller 21 will bring the tongue just previously formed in said tape by the tool 120

115

120

125

130

24, against the front wall of the opening 82 which is situated below said tool, whereupon the further movement of said tape will cause such tongue to be folded under the 5 tape behind the opening from which said tongue was cut.

It will be noted that, during the operation of the mechanism thus far described, the pressure piece 84 will have served two purposes,—first, to prevent the paper tape being lifted following penetration therethrough of the cutting tool 24 when said tool is withdrawn therefrom, without necessitating the lifting of said tool as far above 10 said tape as would otherwise be necessary to assure this result, and, second, that of preventing the tape being lifted an unnecessary distance from the plate 81 by the folded-over tongue formed therein, when said 15 tongue is brought against the plate 81 at the front face of the opening 82 into which it was turned. The holding of the paper tape in close proximity to the plate 81, while said tongue is passing between the opening 20 25 30 35 40 45 50 55 60 65 70 75 80 85 90 95 100 105 110 115 120 125 130

During the passage just referred to of such tongue portion of the tape 23, the one 35 of the feed rollers 22, 22 which is nearest the frame plate of the machine will be moved somewhat farther from the feed roller 21 than the other one of said feed rollers 22; such relative movement between said 40 feed rollers avoids objectionable diversion of the direction of tape movement and is permitted by the formation of the portion of the pressure bar 86 which engages the pivot 87, as best shown in Fig. 7 and as hereinbefore more fully explained.

From the foregoing it will be apparent that successive cycles of energization and deenergization of the magnet 27 will cause corresponding repetitions of the cycle of action of the pallet 112, the cutting tool 24 and the parts moving therewith; and that corresponding cycles of deenergization and energization of the electromagnet 26 will cause corresponding cycles of action of the 50 55 60 65 70 75 80 85 90 95 100 105 110 115 120 125 130

During the running of the paper feeding 65 train hereinbefore described, each revolution

of the shaft 48 will carry the detent arm 51 into engagement with the end 157 of the latch 155, and will thereby cause said latch to release the bar 154. With the arrangement shown, it has been found that, during 70 the formulation of usual signals, the pawls 57 and 58 are almost continuously held out of engagement with the teeth of the wheel 59, (with the possible exception of pauses between so-called "rounds" of a signal) until 75 the conclusion of the signal.

Following the completion of the recording of a signal by the mechanism shown, as just described, effective actuation of the ratchet wheel 59 by the pawls 57 and 58 will 80 be assured by the fact that, during each rotation thereof, the arm 51 will act to cause disengagement of the latch 155 from the bar 154, whereupon the spring 156 will cause the arm 153 to swing to a position which will 85 withdraw the support of the bar 154 from said pawl. When the support of the bar 154 is withdrawn from said pawls, as just described, the spring 65, acting through the arm 62, will swing said pawls toward the 90 wheel 59, and will bring into engagement of the teeth of said wheels whichever one of said pawls is, at the time, positioned for movement in the direction suited for effectively engaging the teeth of said wheel. 95 Assuming, for example, that the eccentrics 55 and 56 are positioned substantially as indicated by Fig. 4, at a time when the pawls 57 and 58 are moved into engagement with the teeth of the wheel 59, as just described,— 100

the spring 65 will act through the projection 64 to urge the pawl 58 into the path of one of the teeth of the wheel 59 and the pawl 57 will rest upon the point of one of the teeth of said wheel. Although the end of 105 the pawl 57 which rests upon the wheel 59 would be thus held higher than the corresponding end of the pawl 58, the opposite ends of said pawls would be so positioned by the eccentrics 55 and 56 that the pawl 58 110 would act through the projection 64 to prevent the arm 62 from bringing the projection 63 into engagement with the pawl 57. It is evident that when the parts are positioned as just described, clockwise rotation 115 of the shaft 48 will first so relatively position the pawls 57 and 58 and the wheel 59 as to permit said pawl 57 to drop to the left of the tooth upon which it has been riding (as viewed in Fig. 4), and that continued 120 rotation of said shaft will thereafter so elevate the portion of said pawl which may cooperate with the projection 63 that the force of the spring 65 will be applied through the arm 62 for the purpose of retaining such 125 engagement by said pawl 57. Thereafter, continued rotation of the shaft 48 will cause rotation of the wheel 59 for an angular distance somewhat in excess of that between adjacent teeth thereof, the pawl 58 being 130

meanwhile drawn over the back of a tooth of said wheel so that the free end of said pawl will be moved in the direction of the projection 64. Inasmuch as the eccentric 5 56 will have thus carried the portion of said pawl 58 which may cooperate with the projection 64 below the position in which said projection is maintained by the pawl 57 acting through the projection 63 and 10 arm 62, said pawl 58 will ride lightly over said tooth, and will not be driven violently past the working face of said tooth, after withdrawal thereof from the path of said pawl.

15 During step by step actuation of the wheel 59, as just described, should either the pin 126 or the pin 127 be disengaged by its cooperating pawls, the resultant action of the marking mechanism will cause the pawls 20 57 and 58 to be withdrawn from the path of the teeth of the wheel 59, whereupon said wheel and the parts moving therewith will again be rotated in response to the spring 66, all as hereinbefore more fully described.

25 It will be noted that whenever the bar 154 withdraws the pawls 57 and 58 from the path of the wheel 59, said pawls are lifted and held clear of said teeth until there has 30 been ample opportunity for said wheel and the parts moving therewith to come to rest following rapid movement thereof (such as is necessary in an instrument of this character) and also giving opportunity for the subsidence of the chattering which usually 35 follows the sudden interruption of rapid movement of such a part, thus avoiding the rapidity of destruction of cooperating surfaces which has occurred in so-called "hopper" mechanism heretofore employed in 40 automatic starting and stopping mechanism for paper feeding trains, especially in high speed instruments where the time of hopper disengagement has exceeded that required for hopper restoration by little, if 45 any, margin.

If the marking mechanism remains at rest, during actuation of the wheel 59 as just described, the cumulative steps imparted thereto by the pawls 57 and 58 will finally carry 50 the lever 61 into the path of the arm 51 and thereby arrest the running of the paper feeding train; thus restoring all of the parts of the mechanism to their normal position.

55 If the signal record produced by operation, such as that just described, occupies an objectionably great space upon the paper tape, this condition can be remedied by changing the adjustment of the pendulum 54 so as to retard the movement of the paper tape and, if necessary, raising the cutting tools 24 and 25 so that—notwithstanding the retarded speed of the paper feed, the marks produced will be suitably spaced. If, 60 on the other hand, there is no occasion for minimizing the space occupied upon the

tape by a given signal, and it is desirable to provide maximum legibility, the cutting tools 24 and 25 should be moved as far toward the paper tape 23 as is possible without destroying necessary working clearance 70 between said tools and said tape; and, if the increase in the size of the marks upon the paper tape then makes it desirable to somewhat increase the speed of the tape, in order to facilitate the reading of signals transmitted at the intended speed, this can be accomplished by adjustment of the pendulum 54.

Having completed adjustment of the speed of movement of the paper tape, as just described, the set screw 71 should be loosened, and the handle 70 should be so adjusted that, with the speed of tape movement already established, the paper feeding mechanism will run, following any action of the marking mechanism, for a time longer than the longest interval between the strokes of any signal, and so that the opening through the paper tape which represents the last stroke of each signal will be carried clear of the signal instrument, as well as of any associated time stamp or other objects which might obstruct the view of the tape as delivered from this instrument. When the handle 70 has been correctly positioned, as just indicated, the set screw 71 should be tightened so as to retain said handle in such position.

Referring now to the contacts shown by Fig. 5, it will be evident that the contacts 73 and 74 will be closed by the insulating rod 78 during the clockwise movement imparted to the wheel 59 by the pawls 57 and 58, and that the point in the movement of said wheel at which said contacts will be closed can be variously fixed by loosening the screw 77 and rotating the arm 76 relatively to the shaft 60. It will be understood by those skilled in this art that, if it is desired to provide means for independently adjusting the relationship between the effective actuation of contacts such as the contacts 73, 74 or 79 and the movement of the wheel 59, such independent adjustability may be obtained by the provision of a desired number of arms, such as the arm 76, each separately adjustable relatively to the shaft 60, and each carrying an insulating rod 78 arranged for cooperation with a desired set or sets of contacts.

If the instrument is employed in connection with a signaling system having signals of two or more classes, one of which classes is characterized by a change in circuit condition of longer duration than corresponding changes in circuit condition incident to signals of another class, if it is desired to arrange contacts such as the contacts 75 or 75' for response to such characterizing current changes,—the arms 169 and 170 should

be so assembled on the shaft 171 that said shaft will be abnormally positioned whenever either the arm 140 or the arm 141 occupies the position which it assumes during such characterizing circuit change; the anvil screw 174 should thereupon be adjusted so that, whenever either said arm 140 or said arm 141 assumes such characterizing position, the sector 164 will be brought into engagement with the part moving with the paper feeding train with which it may co-operate, and the set screw 166 should be so adjusted that when the sector 164 is resting against said screw, the movement of said sector necessary to bring the insulating projection 167 into engagement with the contacts 75 and 75' (as the case may be) will be less than that which would be imparted to said sector by the running of the paper feeding train during such characterizing circuit conditionings and greater than that which would be imparted by similar circuit conditionings of shorter duration.

Assuming adjustment of contacts such as the contacts 73, 74, 75 and 79, as just described in detail, it is evident that, upon the initial actuation of either the cutting tool 24 or the cutting tool 25, as hereinbefore described in greater detail, the resultant counter-clockwise movement of the wheel 59 and parts moving therewith will permit closure of the contact 79, and will also cause momentary closure of the contacts 73 and 74. Such closure of the contact 79 will be suited for causing lighting of a pilot lamp, or other desired indication, to give warning of the fact that the register is in action; but the closure of the contacts 73 and 74 will be of insufficient duration to cause significant response of such devices as may be controlled thereby. If the recorded signal involves a change in circuit condition of duration such that the movement imparted to the sector 164 by the tape 23 or roller 21 (as the case may be) causes said sector to act through the insulating projection 167 to close the contacts 75 or 75' (as the case may be) any emergency signals controlled by said contacts will thereupon be caused to act, to give notice that the signal then being recorded by this instrument is of more than routine nature and therefore requires immediate attention.

After the conclusion of the signal, the comparatively slow clockwise movement imparted to the wheel 59 by the pawls 57 and 58, will act through the insulating rod 78 to cause closure of the contacts 73 and 74, so that the printing circuit of an associate time stamp may have effective and timely energization to the end that the time of receipt of the signal may be imprinted upon the paper tape, and a so-called "hummer" or other arrangement may be set into action for providing a so-called "answer-back" or

acknowledgement of receipt to the person who caused the transmission of the signal recorded by this instrument.

If it is desired to assemble a signal instrument pursuant to this invention, which would be responsive to but one signaling circuit,—this can be variously accomplished by omission of parts. For example, a portion of the marking mechanism comprising the escape wheel 108, the cutting tool 24, and the electromagnet 27 may be omitted; the escape wheel 109 being, in such event, arranged to move with the gear 101, and the parts 102, 105, 106 and 107 being also omitted.

If it is desired to provide an instrument arranged pursuant to this invention for response to more than two signaling circuits, this can be done by various methods, as will be well understood by those skilled in this art without further description herein,—such, for example, as the provision of supplemental sources of driving energy or the further subdivision of the source here shown, in a manner such, for example, as that indicated by Patent No. 646,013, dated March 27th, 1900.

While I have shown and described in considerable detail one specific embodiment of my invention, it should be understood that this is illustrative only, and for the purpose of making clear the nature and objects of my invention, and that various features of this invention may be used separately from the others or in combinations including less than all of such features, and that I do not regard the invention as limited to these details, nor to any of them, except in so far as such limitations are included within the terms of the following claims, in which it is my intention to claim all novelty inherent to my invention as broadly as is permissible in view of the prior art.

What I claim and desire to secure by Letters Patent of the United States of America is:

1. A signal instrument having tape marking and feeding means together with motor driving mechanism for said marking and feeding means and automatic starting and stopping mechanism for said feeding means,—in which said marking means comprises a plurality of independently operable mechanisms each involving an escape wheel, a pallet operable by and controlling the movement of said wheel, a marker operable by oscillation of said pallet and means for controlling such oscillation; said feeding means comprises a tape feed train; said motor mechanism comprises means for applying energy, from a single source, independently to each of said marking mechanisms and to said feed train; and said starting and stopping mechanism comprises a detent lever movable in one direction to arrest the run-

- ning of said train, a spring urging movement of said lever in the opposite direction, a ratchet wheel moving with said lever, eccentrics operable by the running of said train, 5 pawls arranged for alternate reciprocation by said eccentrics and for cooperation with said ratchet wheel to cause rotation thereof such as will move said lever into effective position, means responsive to operation of any 10 one or more of said marking mechanisms for moving said pawls out of the path of said wheel, holding means for at times preventing movement of said pawls into engagement with said wheel, and means operable by the 15 running of said train for terminating the effectiveness of said holding means.
2. A signal instrument having tape marking and feeding means together with motor driving mechanism for said marking and 20 feeding means and automatic starting and stopping mechanism for said feeding means,—in which said marking means comprises a plurality of independently operable mechanisms each involving an escape wheel, 25 a pallet operable by and controlling the movement of said wheel, a marker operable by oscillation of said pallet and means for controlling such oscillation; said feeding means comprises a tape feed train; said motor mechanism comprises means for applying energy, from a single source, independently to each of said marking mechanisms and to said feed train; and said starting and stopping mechanism comprises a detent 30 lever movable in one direction to arrest the running of said train, a spring urging movement of said lever in the opposite direction, a ratchet wheel moving with said lever, eccentrics operable by the running of said 35 train, pawls arranged for alternate reciprocation by said eccentrics and for cooperation with said ratchet wheel to cause rotation thereof such as will move said lever into effective position, and means responsive to 40 operation of any one or more of said marking mechanisms for moving said pawls out of the path of said wheel.
3. A signal instrument comprising a motor spring, differential gearing through 45 which the torque from one of the ends of said motor spring is subdivided, and a plurality of independently controlled marking mechanisms and a tape feeding train each independently operable by the torque of said 50 motor spring as delivered by respective ends thereof and as subdivided by said gearing.
4. A signal instrument having motor driven tape marking and feeding means, together with automatic starting and stopping 55 mechanism for said feeding means,—in which said marking means comprises a mechanism involving an escape wheel, a pallet operable by and controlling the movement of said wheel, a marker operable 60 by oscillation of said pallet and means for 65

controlling such oscillation; said feeding means comprises a tape feed train; and said starting and stopping mechanism comprises a detent structure having a toothed portion, arranged to arrest the running of said train 70 when actuated in one direction and to which a tendency is imparted for actuation in the opposite direction, eccentrics operable by the running of said train, pawls arranged for alternate reciprocation by said eccentrics and 75 for cooperation with the teeth of said structure to cause actuation thereof in said first named direction, and means responsive to operation of said marking mechanism for moving said pawls out of the path of the 80 toothed portion of said structure.

5. A signal instrument having tape marking mechanism comprising an escape wheel, a pallet operable by and controlling the movement of said wheel, a marker operable 85 by oscillation of said pallet and means for controlling such oscillation, said means involving a toggle arranged for straightening thereof by and during the oscillation of said pallet and for acting when straightened, to 90 arrest such oscillation at a stage thereof when said pallet is so positioned as to be operable by said escape wheel at least advantage.

6. A signal instrument having a tape 95 marking mechanism comprising an escape wheel, a pallet operable by and controlling the movement of said wheel, a marker operable by oscillation of said pallet and means for controlling such oscillation, said means 100 involving a toggle arranged for straightening thereof by and during the oscillation of said pallet.

7. A signal instrument having a tape marking mechanism comprising an escape 105 wheel, a pallet operable by and controlling the movement of said wheel, a marker operable by oscillation of said pallet and means for controlling such oscillation.

8. A signal instrument having motor driven tape marking and feeding means together with automatic starting and stopping mechanism for said feeding means,—in which said feeding means comprises a tape feed train, and said starting and stopping mechanism comprises detent structure having a toothed portion, arranged to arrest the running of said train when actuated in one direction and to which a tendency is imparted for actuation in the opposite direction, eccentrics operable by the running of said train, pawls arranged for alternate reciprocation by said eccentrics and for cooperation with the teeth of said structure to cause actuation thereof in said first named 115 direction, and means responsive to operation of said marking mechanism for moving said pawls out of the path of the toothed portion of said structure.

9. A signal instrument having a time train 120

- with associated automatic starting and stopping mechanism comprising detent structure having a toothed portion, arranged to arrest the running of said train when actuated in one direction and to which a tendency is imparted for actuation in the opposite direction, eccentrics operable by the running of said train, pawls arranged for alternate reciprocation by said eccentrics and for cooperation with the teeth of said structure to cause actuation thereof in said first named direction, means whereby said pawls may be moved out of the path of the toothed portion of said structure, and means for varying the extent of the permitted actuation of said structure in said second named direction. 10
10. A signal instrument having a time train with associated automatic starting and stopping mechanism comprising detent structure having a toothed portion, arranged to arrest the running of said train when actuated in one direction and to which a tendency is imparted for actuation in the opposite direction, eccentrics operable by the running of said train, pawls arranged for alternate reciprocation by said eccentrics and for cooperation with the teeth of said structure to cause actuation thereof in said first named direction, and means whereby said pawls may be moved out of the path of the toothed portion of said structure. 15
20. A signal instrument having a time train with associated automatic starting and stopping mechanism comprising detent structure having a toothed portion, arranged to arrest the running of said train when actuated in one direction and to which a tendency is imparted for actuation in the opposite direction, eccentrics operable by the running of said train, pawls arranged for alternate reciprocation by said eccentrics and for cooperation with the teeth of said structure to cause actuation thereof in said first named direction, means whereby said pawls may be moved out of the path of the toothed portion of said structure. 25
30. A signal instrument having a time train with associated automatic starting and stopping mechanism comprising detent structure having a toothed portion, arranged to arrest the running of said train when actuated in one direction and to which a tendency is imparted for actuation in the opposite direction, eccentrics operable by the running of said train, pawls arranged for alternate reciprocation by said eccentrics and for cooperation with the teeth of said structure to cause actuation thereof in said first named direction, means whereby said pawls may be moved out of the path of the toothed portion of said structure, holding means for at times preventing movement of said pawls into engagement with said toothed portion, and means operable by the running of said train for terminating the effectiveness of said holding means. 35
40. A signal instrument having a time train with associated automatic starting and stopping mechanism comprising detent structure having a toothed portion, arranged to arrest the running of said train when actuated in one direction and to which a tendency is imparted for actuation in the opposite direction, eccentrics operable by the running of said train, pawls arranged for alternate reciprocation by said eccentrics and for cooperation with the teeth of said structure to cause actuation thereof in said first named direction, means whereby said pawls may be moved out of the path of the toothed portion of said structure, and holding means for at times preventing movement of said pawls into engagement with said toothed portion. 45
50. A signal instrument having a time train with associated automatic starting and stopping mechanism comprising detent structure having a toothed portion, arranged to arrest the running of said train when actuated in one direction and to which a tendency is imparted for actuation in the opposite direction, eccentrics operable by the running of said train, pawls arranged for alternate reciprocation by said eccentrics and for cooperation with the teeth of said structure to cause actuation thereof in said first named direction. 55
60. A signal instrument having a time train with associated automatic starting and stopping mechanism comprising detent structure having a toothed portion, arranged to arrest the running of said train when actuated in one direction and to which a tendency is imparted for actuation in the opposite direction, eccentrics operable by the running of said train, pawls arranged for alternate reciprocation by said eccentrics and for cooperation with the teeth of said structure to cause actuation thereof in said first named direction. 65
65. A signal instrument having a time train with associated automatic starting and stopping mechanism comprising detent structure having a toothed portion, arranged to arrest the running of said train when actuated in one direction and to which a tendency is imparted for actuation in the opposite direction, eccentrics operable by the running of said train, pawls arranged for alternate reciprocation by said eccentrics and for cooperation with the teeth of said structure to cause actuation thereof in said first named direction. 70
75. A signal instrument having a time train with associated automatic starting and stopping mechanism comprising detent structure having a toothed portion, arranged to arrest the running of said train when actuated in one direction and to which a tendency is imparted for actuation in the opposite direction, eccentrics operable by the running of said train, pawls arranged for alternate reciprocation by said eccentrics and for cooperation with the teeth of said structure to cause actuation thereof in said first named direction, and means whereby said pawls may be moved out of the path of the toothed portion of said structure. 80
85. A signal instrument having a time train with associated automatic starting and stopping mechanism comprising detent structure having a toothed portion, arranged to arrest the running of said train when actuated in one direction and to which a tendency is imparted for actuation in the opposite direction, eccentrics operable by the running of said train, pawls arranged for alternate reciprocation by said eccentrics and for cooperation with the teeth of said structure to cause actuation thereof in said first named direction, and means whereby said pawls may be moved out of the path of the toothed portion of said structure. 85
90. A signal instrument having a movable toothed member, a pair of diametrically opposite eccentrics, pawls arranged for alternate reciprocation by said eccentrics and for cooperation with the teeth of said member to cause actuation thereof, and a potentially active means for urging movement of said pawls toward said member, the direction of rotation of said eccentrics and the manner of the application of said means to said pawls such that at given times said means will be applied only to such one of the pawls as is then positioned for actuation to move said member. 95
100. A signal instrument having means for propelling a tape and marking mechanism adapted for forming tongues in such a tape, in combination with guide structure situated adjacent to the path of intended movement of such tape away from said marking mechanism, a wall of such structure being so situated as to be disposed in the path of tongues formed in such tape by said marking mechanism, and a pressure piece resiliently urged toward said structure and having a wall thereof substantially in alignment with said wall of said structure and so disposed that such intended tape movement will cause tongues formed in such tape to pass between said walls. 105
110. A signal instrument having means whereby a tape may be caused to move in a predetermined plane and mechanism for marking such a tape, said mechanism comprising a cutting tool and operating means therefor, involving construction for moving said tool to and through such plane and whereby the extent of the movement of said tool through and beyond such plane may be variously adjusted. 115
120. A signal instrument having means whereby a tape may be caused to move in a predetermined plane and mechanism for marking such a tape, said mechanism comprising a cutting tool and operating means therefor, involving construction for moving said tool to and through such plane and whereby the extent of the movement of said tool through and beyond such plane may be variously adjusted. 125
130. A signal instrument having means whereby a tape may be caused to move in a predetermined plane and mechanism for marking such a tape, said mechanism comprising a cutting tool and operating means therefor, involving construction for moving said tool to and through such plane and whereby the extent of the movement of said tool through and beyond such plane may be variously adjusted. 130

17. A signal instrument having marking mechanism operable to form tongues in a paper tape and tape feeding means comprising feed rollers one of which is arranged for 5 rotation around a fixed axis and others of which are so supported as to be adapted for independent rotation around axes substantially parallel to and movable toward and away from said fixed axis, involving construction and arrangement whereby individual ones of said last named rollers may be so differently spaced from said first named rollers as to assure substantial uniformity in 10 direction of tape travel resultant from the rotation of said first named roller irrespective of travel between said rollers of portions of such a tape carrying such tongues folded thereunder.

18. In a signal instrument having mechanism operable in response to respective signal impulses and a train arranged for operation at a predetermined speed,—starting and stopping mechanism arranged to arrest the running of said train only when in normal condition, in combination with contacts 20 so associated with said starting and stopping mechanism as to be abnormally positioned during restoration thereof, and means for variously fixing the point during such 25 restoration at which said abnormal positioning will occur.

19. In a signal instrument having a time controlled mechanism and a plurality of independently operable signal responsive mechanisms,—circuit controlling means involving operating mechanism comprising a 30 sector-like piece the periphery of which is suited for so engaging a part moving with said time controlled mechanism as to be moved therewith, a resilient flexible arm to which said piece is pivotally attached, said arm arranged to yieldingly resist movement thereof in such direction as would carry said piece to a position where it may be rotated 35 in one direction by engagement of the periphery thereof with said time controlled part, a spring for rotating said piece in the opposite direction, means for varying the extent of the rotation of said piece in said second named direction, means for abnormally conditioning an electric circuit by rotation of said piece in opposition to said spring to a predetermined position, mechanism comprising means arranged for actuation by 40 any one of said independently operable mechanisms for applying to said arm, at a point susceptible of movement independently of the pivotal connection thereto of said piece, a tendency for movement of said arm such as will carry said piece toward the aforesaid time controlled part, and means for varying the extent of the movement which may be imparted to said arm by said means.

65 20. In a signal instrument having a time

controlled mechanism and a signal responsive mechanism,—circuit controlling means involving operating mechanism comprising a sector-like piece the periphery of which is suited for so engaging a part moving with 70 said time controlled mechanism as to be moved therewith, a resilient flexible arm to which said piece is pivotally attached, said arm arranged to yieldingly resist movement thereof in such direction as would carry said piece to a position where it may be rotated 75 in one direction by engagement of the periphery thereof with said time controlled part, a spring for rotating said piece in the opposite direction, means for abnormally conditioning an electric circuit by rotation of said piece in opposition to said spring to a predetermined position, and mechanism comprising means arranged for actuation by 80 said signal responsive mechanism for applying to said arm, at a point susceptible of movement independently of the pivotal connection thereto of said piece, a tendency for movement of said arm such as will carry said piece toward the aforesaid time controlled part.

21. In a signal instrument having a time controlled mechanism and a plurality of independently operable mechanisms each involving a controlling electromagnet and a 90 part moving in response to energization and deenergization thereof,—circuit controlling means involving operating mechanism comprising a sector-like piece the periphery of which is suited for so engaging a part moving with said time controlled mechanism as to be moved therewith, an arm to which said piece is pivotally attached, potentially active means urging movement of said arm away from a position where said piece may 100 be rotated in one direction by engagement of the periphery thereof with said time controlled part, potentially active means for rotating said piece in the opposite direction, means for varying the extent of permitted 105 rotation of said piece in said second named direction, means for abnormally conditioning an electric circuit by rotation of said piece in said opposite direction to a predetermined position, mechanism comprising 110 means for applying to said arm a tendency for movement such as will carry said piece toward the aforesaid time controlled part, said last named means arranged for actuation by the electromagnetically responsive 120 parts of said marking mechanisms and for alternative adjustability relative to said parts whereby one adjustment will condition said means for causing movement of said arm in said first named direction whenever 125 any one of said parts has moved in response to magnetization of its associated controlling electromagnet, and another adjustment will condition said means for causing such movement of said arm whenever any one of 130

said parts has moved in response to demagnetization of its associated controlling magnet, and means comprising a set screw carried by said arm for varying the extent of 5 the movement which may be imparted to said arm by said means.

22. In a signal instrument having a time controlled mechanism and a plurality of independently operable signal responsive 10 mechanisms,—circuit controlling means involving operating mechanism comprising a sector-like piece the periphery of which is suited for so engaging a part moving with said time controlled mechanism as to be moved therewith, an arm to which said piece is pivotally attached, potentially active 15 means urging movement of said arm away from a position where said piece may be rotated in one direction by engagement of the 20 periphery thereof with said time controlled part, potentially active means for rotating said piece in the opposite direction, means for varying the extent of permitted rotation of said piece in said second named direction, means for abnormally conditioning 25 an electric circuit by rotation of said piece in said opposite direction to a predetermined position, mechanism comprising means arranged for actuation by any one of said independently operable mechanisms for applying 30 to said arm a tendency for movement thereof such as will carry said piece toward the aforesaid time controlled part,

and means for varying the extent of the movement which may be imparted to said 35 arm by said means.

23. In a signal instrument having a time controlled mechanism and a signal responsive mechanism,—circuit controlling means involving operating mechanism comprising 40 a sector-like piece the periphery of which is suited for so engaging a part moving with said time controlled mechanism as to be moved therewith, an arm to which said piece is pivotally attached, potentially active 45 means urging movement of said arm away from a position where said piece may be rotated in one direction by engagement of the periphery thereof with said time controlled part, potentially active means for rotating 50 said piece in the opposite direction, means for varying the extent of permitted rotation of said piece in said second named direction, means for abnormally conditioning an electric circuit by rotation of said piece in said 55 opposite direction to a predetermined position, and mechanism comprising means arranged for actuation by said signal responsive mechanism for applying to said arm a tendency for movement thereof such as will 60 carry said piece toward the aforesaid time controlled part.

In witness whereof, I hereunto subscribe my name, this 11 day of March, 1925.

GEORGE ERNEST KING.
